UNITED STATES PATENT OFFICE.

ANDREW V. CLELAND, OF MINNEAPOLIS, MINNESOTA.

GRAIN-CLEANING MACHINE.

Application filed August 1, 1921. Serial No. 488,902.

To all whom it may concern:

Be it known that I, ANDREW V. CLELAND, a citizen of the United States, resident of Minneapolis, county of Hennepin, State of Minnesota, have invented certain new and useful Improvements in Grain-Cleaning Machines, of which the following is a specification.

The primary object of my invention is to provide an improved feeding and air suction arrangement for grain cleaners and one that will have a higher degree of efficiency in operation and with which I am able to effect not only economy as regards space occupied in the machine but also the cost of construction.

A further object is to provide an apparatus of the type described, which can be operated efficiently with less power than usually is required in machines of this kind.

A further object is to provide improved means for handling the repeat or return, so called, subjecting it a second time to the air suction, with provision for distributing it evenly over the sieves without possibility of flooding due to variation in conditions of the grain.

A further object is to provide a machine of the type described, in which fewer adjustments are provided, thus simplifying the operation and care of the machine, the adjustments being such that the volume of air passing through the discharge pipe can not be reduced but will be uniform and continuous, thus preventing clogging of the discharge pipe.

A further object is to provide a machine of the type described, in which all wearing parts are easily accessible and removable for repair or replacement. The surfaces in a grain cleaning machine being exposed to contact of the grain carried along by the air blast, considerable replacement and repair are frequently necessary, hence the means of convenient access and removal.

The invention consists generally in various constructions and combinations, all as hereinafter described and particularly pointed out in the claims.

In the accompanying drawings forming part of this specification,

Figure 1 is a vertical sectional view

through a grain cleaning machine embodying my invention,

Figure 2 is an enlarged detail view of a portion of the hopper and the removable dust duct or passage,

Figure 3 is a detail sectional view on the line 3—3 of Figure 2,

Figure 4 is a detail sectional view on the line 4—4 of Figure 2,

Figure 5 is an outside view of Figure 4, showing the means for operating the shutter blades,

Figure 6 illustrates the manner of mounting the dust duct or passage in the machine casing,

Figure 7 is a horizontal sectional view, showing the manner of clamping the sections composing the dust duct together.

In the drawing, 2 represents a grain hopper, to which the grain to be cleaned or separated is fed by a suitable means, not shown. 3 is a repeat hopper, separated from the hopper 2 by a fixed partition or wall 4. In the lower portion of the hopper is a feed opening or throat 5, which communicates with both the hoppers 2 and 3 and receives the grain therefrom. A division board 6 is hinged at 7 to the lower end of the wall 4 and operates as a means for distributing the material in the hopper 3 over its full width, the board swinging back and forth across the throat and increasing or decreasing the size of the opening leading from the hopper, according to its position therein.

A screw 8 is provided for adjusting the division board in the hopper. A feed roll 9 is provided beneath the throat 5 and over which the material flows from the hopper to the bank of sieves beneath. A feed plate 11 is hinged at 12 above the feed roll and is provided with an arm 13, pivotally connected with the rod 15 by means of which the feed plate may be oscillated to increase or decrease the distance between its lower edge and the feed roller and regulate the volume of grain passing over the feed roller.

Above the feed roller is a box 16 formed in the casing and open at the top, but normally closed by the frame 17 in which a series of shutter blades 18 are mounted and adjustable on a longitudinal axis by means of cranks 19 and a connecting bar 20 in a

manner similar to the construction and operation of an ordinary rocking window blind. By means of these shutter blades the operator of the machine can regulate the admission of air to the box 16 and whenever desired, the frame 17 may be removed to entirely expose the open top of the box.

Within the box I arrange a removable dust duct or passage made up preferably in sections, consisting of blocks 21, 22 and 23, alternating with sheet metal walls 24 and 25 and secured together through said blocks and walls by suitable means, such as rods 26. The arrangement of these blocks and sheet metal plates provides a dust duct 27 which communicates at its lower end with the throat 5 above the feed roll and this duct extends vertically to the upper portion of the box 16 and thus describes a long, gradual curve from the side of the box adjacent the hopper to a point near the other side and is then deflected inwardly toward the starting point, this being accomplished by turning the wall 25 inwardly upon itself and then bending the end of the wall 24 in the same direction and finally turning the extremity 24^a of this wall outwardly and upwardly to form a narrow or contracted throat or passage 28 between this wall and the adjacent wall of the box 16 leading to an opening 29, which communicates with the suction fan 30 arranged within a casing 31. The dust duct 27 is thereby made comparatively long. It is of substantially the same transverse area from one end to the other, consequently there will be no chance for the air to expand in the duct, with the objectionable results.

The walls are formed in smooth, continuous curves and there are no sharp bends or breaks to interrupt or deflect the air currents and the dust flowing through the duct. The duct is removable from the box and hence access may be easily had to all the wearing parts for replacement and repairs.

It is fastened in the box by suitable means, preferably a wedge 32, which is secured to the wall of the box 16. The outer block of the duct is arranged with a similar wedge 50 face 32^a, which engages the face of the wedge 32 when the duct is dropped into place, thereby forcing the duct against the opposite side of the box and clamping it securely therein, with the throat of the duct adjacent to and above the passage 33, into which the grain is delivered by the feed roller.

A chamber 34 communicates with the exit opening of the duct and is provided with a screw conveyer 35 for receiving the grain and delivering it at the side of the machine. A deflector 36 is mounted at 37 and adapted to be raised and lowered to increase or decrease the distance between the deflector and the walls of the duct and hasten the delivery of the grain to the screw

conveyer or retard such delivery. This is indicated by the different positions of the deflector in Figure 2, the full line position operating to deliver the grain rapidly to the screw conveyer, while the dotted line or substantially horizontal position serves to retard the grain and subject it for a longer period to the action of the air currents. This deflector is operated by suitable means, such as a lever 38 connected with a shaft 39 on which arms 40 are mounted in position to engage the underside of the deflector and lift it to its dotted line position.

The casing of the screw conveyer preferably comprises a wall 41 enclosing one end 80 and the middle portion of the conveyer, while the other end has a casting 42 secured by bolts 43 or other suitable means to the wall of the machine and having a bearing 44 for one end of the screw. The other end of the screw has a bearing 45 from which the screw may be readily removed when the casting 42 is detached from the casing. The usual driving sprocket 46 is provided on one end of the screw. This manner of mounting the screw conveyer allows convenient separation of the parts for cleaning, examination or repairs, it only being necessary to loosen the securing bolts and draw the screw conveyer entirely out of its bearings in the machine.

When the suction fan is in operation, a vacuum will be created in the duct and air currents will rush up the passage 33 and into the duct and to regulate the flow of such currents, I provide a gate 47, hinged at 48 and operated by means of a rod 49 having a spring 50 and a thumb nut 51 engaging the threaded end of the rod and by means of which the gate may be adjusted and yieldingly held to control the flow of air currents upwardly past the feed roller and through the material and into the dust duct. A clip 25^a is mounted on the wall 25 to slide on the plate 48^a to which the gate 47 is connected.

It will be understood from the foregoing that when the suction fan is operated, a vacuum will be created in the dust passage and the currents of air, carrying the lighter particles of grain and dust, will pass up into this dust passage and flow upwardly and downwardly therein without expanding and finally will precipitate the heavier material into the screw conveyer as the air expands after leaving the comparatively confined area of the dust passage. The degree of suction of this passage may be regulated by the adjustment of the shutters in the top of the box. These shutters may be opened when air will enter between them and flow directly to the fan, and there will be no vacuum created in the dust passage. The shutters may be entirely closed and thereupon a strong suction will be created in the

dust passage and the dust and lighter particles of grain will be lifted out of the stream as it flows over the feed roller. After the lighter grain passes through the dust passage, it will be deposited by gravity in the screw conveyer beneath.

If the deflector blade 36 is raised to its dotted line position, the space for the air is sufficiently reduced to cause it to move 10 with sufficient rapidity to carry the lighter portion of the product beyond the conveyer and into the fan. By the simple attachment of this deflector, the character of the material delivered to the screw conveyer may 15 be regulated.

Communicating with the fan casing is a discharge pipe 52. Whenever desired, the shutters in the top of the duct box may be adjusted to control the flow of air through 20 the duct, reducing the power of the suction and regulating perfectly the weight of material drawn into the dust duct without reducing the volume of air admitted to the fan and the discharge pipe, this volume being continuous and uninterrupted, and preventing clogging in the discharge pipe. In 25 operation, therefore, the simple adjustment of the shutter above the dust duct regulates the degree of suction and makes it unnecessary to change the adjustment of the gate 30 47 when it is desired to affect the volume of air passing through the discharge pipe.

At one side of the machine casing I provide a repeat elevator 53 having a spout 54 which delivers the repeat material to the repeat hopper 3. From thence the material passes by the division board 6 to the feed roll, is mixed with the material from the main hopper, and again subjected to air 40 suction. A more effectual cleaning and separation of the grain is thereby obtained. Generally in machines of this type, the repeat is delivered directly to the sieves, but in my improved construction a separate compartment is provided in the hopper for the repeat, provision being made for regulating its volume of feed to mingle with the other grain and the repeat is subjected to the action of the suction fan a second time. 45 Whenever desired, in the operation of the machine, the shutters above the dust duct may be opened so that practically all the air entering will flow past these shutters to the fan and the suction and vacuum in 50 the dust duct will be destroyed, or whenever desired, the degree of this suction may be instantly controlled by the adjustment of the shutters.

Opposite the sieves 10 is the usual blast 60 fan 55 and below the sieves are the usual screens 56 and 57 arranged to deliver material to the spouts 58 and 59.

It will be noted from the foregoing description that the air currents flowing 65 through the dust duct will be uniform and

continuous. There being no sharp corners nor bends in the duct, the flow will be uninterrupted and make for greater efficiency of the machine. There being no fluctuations in the flow, there will be no danger of clogging in the discharge pipe, which frequently happens where the currents of air are intermittent or irregular. Cleaning and replacing of the parts of the dust duct can be readily accomplished, as the manner of mounting permits the convenient separation of the dust duct from the machine, allowing not only access to the walls of the duct, but also exposing the regulating deflector or blade and the screw conveyer and feed roll. 70

The dimensions of the dust duct and the details of construction thereof may, of course, be modified materially and still be within the scope of my invention.

I claim as my invention:

1. A grain separating machine having a hopper provided with a chamber for the main feed and a chamber for the repeat material, with means for delivering the repeat to said repeat chamber, and means for regulating the mixture of the material in the main feed chamber with the repeat material. 85

2. In a grain separating machine, a hopper having a partition dividing it into a main feed chamber and a repeat feed chamber, a division board mounted to regulate the flow from either of said chambers, and a repeat elevator arranged to deliver the repeat material to its chamber in said hopper. 95

3. In a grain separating machine, a hopper, a partition wall therein dividing the hopper into a main feed chamber and a repeat chamber, a division board hinged to the lower end of said partition wall and arranged to shut off the flow of material wholly or partially from each of said chambers, and means for delivering the repeat material to said repeat chamber. 100

4. In a grain cleaning machine, a feed hopper having a discharge throat, a suction fan and discharge pipe therefor, and a tortuous dust duct interposed between said fan and hopper throat for conducting the dust from said throat to said fan, and said duct being mounted for removal for replacement or repairs. 110

5. In a grain cleaning machine, a feed hopper having a discharge throat, a suction fan, a box arranged between said fan and throat, and a dust duct removably fitting within said box and communicating with said throat and with said fan. 120

6. In a grain cleaning machine, a feed hopper having a discharge throat, a suction fan, a box arranged between said fan and throat, and a dust duct removably fitting within said box and communicating with said throat and with said fan, said duct being composed of blocks alternating with 125

- curved sheets and means passing through said blocks and sheets for securing them together.
7. In a grain cleaning machine, a feed hopper having a discharge throat, a suction fan, a dust duct communicating with said throat and with said fan, said duct being of substantially uniform cross sectional area from the intake to the exhaust thereof.
- 10 8. In a grain cleaning machine, a feed hopper having a discharge throat, a suction fan, a dust duct interposed between said throat and fan and communicating therewith, said duct being of substantially the same cross sectional area from end to end and having curved smooth surfaces substantially continuous and unbroken, for the purpose specified.
- 15 9. In a grain cleaning machine, a hopper having a discharge throat, a suction fan, a dust duct interposed between said fan and throat and having a substantially straight entrance, a curved middle portion, and a discharge end that is extended inwardly toward the entrance terminating in an orifice leading to said fan, the passage through said duct being unobstructed and of substantially uniform cross sectional area from end to end.
- 20 10. In a grain cleaning machine, a feed hopper having a discharge throat, a feed roll adjacent said throat, a suction fan, a dust duct interposed between said fan and throat and having a tortuous passage of uniform cross sectional area, wherein a vacuum is created by the operation of said fan, a gate adjacent said feed roll for regulating the flow of air to said air duct, past said throat, and means for introducing air to said fan independently of said duct.
- 25 11. In a grain cleaning machine, a feed hopper having a discharge throat, a suction fan, a dust box between said fan and throat, a dust duct mounted in said box and communicating with said throat and with said fan, and wherein a vacuum is created by the operation of said fan, a gate for regulating the flow of air to said duct past said throat, and means for admitting air to said box outside of said duct for regulating the degree of suction in said duct.
- 30 12. In a grain cleaning machine, a feed hopper having a discharge throat, a suction fan, a dust box between said fan and throat, a dust duct mounted in said box and communicating with said throat and with said fan, and wherein a vacuum is created by the operation of said fan, a gate for regulating the flow of air to said duct past said throat, and shutters mounted in the wall of said box for admitting air to said fan outside said duct and controlling the degree of suction therein.
- 35 13. In a grain cleaning machine, a feed hopper having a discharge throat, a suction fan, a dust duct interposed between said fan and throat, a frame removably mounted on said box and shutters mounted in said frame for admitting air to said fan outside said duct and regulating the degree of suction in said duct.
- 40 14. In a grain separating machine, a feed hopper having a discharge throat, a suction fan, a dust duct interposed between said fan and throat and wherein a vacuum is created by the operation of said fan, a conveyer arranged beneath the exit of said duct to receive the material precipitated thereby, and a deflector mounted above said conveyer for controlling the delivery of the material from said duct to said conveyer.
- 45 15. In a grain cleaning machine, a feed hopper having a discharge throat, a suction fan, a dust duct communicating at one end with said throat and at the other end with said fan, a conveyer arranged beneath the discharge opening of said duct to receive the material precipitated therefrom, there being a passage formed between said conveyer and duct leading to said fan, and a deflector comprising a plate mounted above said conveyer and a means for tilting said deflector to hasten the delivery of the material from said duct to said conveyer or retard such delivery and contract the passage leading from said duct to said fan.
- 50 16. In a grain cleaning machine, a feed hopper having a discharge throat, a suction fan, a dust box having an air intake, a dust duct having a tortuous passage removably mounted in said box and communicating with said throat and with said fan and in which duct a vacuum is created by the operation of said fan.
- 55 17. In a grain cleaning machine, a feed hopper having a discharge throat, a suction fan, a dust box, a dust duct having a tortuous passage removably mounted in said box and communicating with said throat and with said fan and in which duct a vacuum is created by the operation of said fan, and means for admitting air to said box outside the walls of said duct.
- 60 18. In a grain cleaning machine, a feed hopper having a discharge throat, a suction fan, a dust box, a dust duct having a tortuous passage removably mounted in said box and communicating with said throat and with said fan and in which duct a vacuum is created by the operation of said fan, and shutters mounted in said box for admitting air to said fan and box.
- 65 19. In a grain cleaning machine, a feed hopper having a discharge throat, a suction fan and dust box interposed between said fan and throat, a dust duct mounted in said

box and communicating with said throat and fan and wherein a vacuum is created by the operation of said fan, and means for controlling the degree of suction through said 5 duct.

20. In a grain cleaning machine, a feed hopper having a discharge throat, a suction fan, a dust box between said fan and throat, a dust duct removably mounted in said box

and having a substantially straight receiving section communicating with said throat, and an inwardly curved discharging section communicating with said fan and means for regulating the flow of air through said duct.

In witness whereof, I have hereunto set 15 my hand this 27th day of July, 1921.

ANDREW V. CLELAND.
